UNITED STATES PATENT OFFICE.

FREDERIC K. HEYER, OF STAMFORD, CONNECTICUT, ASSIGNOR TO THE YALE & TOWNE MANUFACTURING COMPANY, OF STAMFORD, CONNECTICUT.

LOCK.

Application filed January 6, 1927. Serial No. 159,422.

This invention relates to improvements in locks, one object of the invention being to provide means to safeguard the lock against surreptitious operation.

5 A further object is to provide means which will lock the plug member against turning, in the event an attempt be made to operate the lock by driving a chisel or other instrument into the key-way and then attempting to 10 forcibly turn the plug with the use of a wrench applied to the chisel or other instrument.

With these and other objects in view, the invention consists in certain novel features as 15 hereinafter set forth and pointed out in the claims.

In the accompanying drawings:

Figure 1 is a longitudinal sectional view 20 of a lock structure, showing an embodiment of my invention;

Figure 1^a is a sectional view taken at right angles to Figure 1;

Figure 1^b is a fragmentary view;

Figure 2 is a front end view;

25 Figure 3 is a forward end view;

Figure 4 is a transverse section on the line 4-4 of Figure 1;

Figure 5 is a transverse sectional view on the line 5-5 of Figure 1;

30 Figure 6 is a separate view of the forward plate of the plug structure;

Figure 7 is a view in side elevation of the plug;

Figure 8 is a longitudinal sectional view 35 of the lock cylinder, showing also the forward end plate for the plug;

Figure 9 is a longitudinal sectional view, partly in elevation, showing a modification;

40 Figure 10 is an end view of the structure shown in Figure 9;

Figure 10^a is a view showing another modification, and

Figures 11 and 12 are views showing different forms of locking bar.

45 In the embodiment of the invention shown in Figures 1 to 8 of the drawings, a lock cylinder or casing is indicated at 1 and the same is provided interiorly with recesses 2 for the reception of the tumblers (not shown) carried by a plug structure 3. This plug structure comprises a core member 4 and a reinforcing shell 5, the latter being provided at its forward end with lugs or extensions 6 which pass through slots 7 in an end plate 8

a similar structure being disclosed in my previous application Serial No. 141,302, and may be modified so far as my present invention is concerned.

55 A groove 9 is formed within the cylinder near its forward end and receives the peripheral portion of the plate 8 in such manner that said plate may turn with the plug. A roll back cam 10 is carried by the plate 8 and is intended to manipulate a transversely disposed bolt (not shown), as will be readily 60 understood.

The plug is provided with a cap or head 11 which is slotted as at 12 in line with the key-way of the plug and the peripheral edge portion of said head may be provided with an 70 annular groove 13 to receive a locking wire 14 which also enters a groove 15 in the inner wall of the cylinder and said groove 15 is somewhat elongated transversely so that slight longitudinal movement of the plug 75 may be permitted. The locking wire may be inserted through a tangential hole 16 in the cylinder wall, as disclosed in application filed by Maxwell C. Maxwell, Serial No. 126,556. The cylinder wall is formed with a 80 recess at one end as at 17 (one end of said recess forming a shoulder 18) to permit limited longitudinal movement of the plug head for a purpose hereinafter explained.

The shell 5 of the plug is provided in one 85 end with recesses 5^a to receive lugs 5^b projecting from the case 4 of the plug. The case 4 abuts against the cap or head 11 of the plug and terminates a short distance from the plate 8 at the forward end of the shell 5 as indicated at 5^c,—the lugs 5^b insuring a clearance 90 between the cap 11 and shell 5. Upon initial movement of the cap 11 toward the shell 5 as hereinafter described, the lugs 5^b will be sheared off.

A longitudinal groove 19 (preferably dovetail in form) is formed in the inner wall of the lock cylinder and receives a locking bar 20, one end of which is located behind the plug head 11 and in line with the other end 100 of said bar, a notch or slot 21 is made in the plug end plate 8. The bar 20 fits rather tightly in the groove in the cylinder wall but it may be forced forwardly under conditions presently explained and caused to engage the 105 notched portion of the plate 8 so as to positively lock the plug 3 against turning.

Should attempt be made to surreptitiously

force the lock by inserting a chisel or other instrument into the keyway of the plug, the latter would be forced forwardly and the head of the plug moving in the recess 17 and engaging the bar 20, would force the latter forwardly and cause it to enter the notch 21 in the plug plate 8, thus positively locking the plug against rotation, even though power be applied to the chisel with the use of a wrench in 10 an attempt to turn the plug.

In the embodiment of the invention shown in Figure 9, a transversely movable bolt 22 carried by the lock cylinder is shown. In this construction, the cylinder 23 carries a locking 15 rod 24 intended to be moved into the transmission casing of a motor car whereby to lock the shifter mechanism, and in order that such movement of the rod 24 may be effected, the lock cylinder 23 must be capable of longitudinal 20 movement. To normally lock the cylinder 23 and rod 24 against movement, the transverse bolt 22 will be caused to engage a suitable easing (not shown) in which the cylinder is movable. In the embodiment of the invention 25 shown in Figure 9, a locking bar 25 is mounted in a suitable groove 26 in the cylinder wall and is engageable by the head 11 of the plug 3 upon attempt to force the lock in the manner previously explained, and adapted by 30 pressure of the head to be forced forwardly behind the bolt 22, so that retraction of said bolt will be prevented and as said bolt is connected with the lock plug through the medium of the roll back cam 10, the plug will be locked 35 against turning. This locking bar 20 or 25 may be made straight as shown in Figure 12 and fit friction tight in its groove 10 or 26 or the same may have a slight shoulder or enlargement 27, (Figure 11) which in case of 40 attack, as previously described, will be driven forwardly into the side wall of the groove in the cylinder and thus be held securely in its locking position.

While the member for locking the plug to 45 the cylinder is shown as being mounted in the wall of the cylinder and adapted to be moved into locking relation to the plug, the plug may be made to carry a locking member adapted to be moved into locking relation to the cylinder, 50 as shown in Figure 10. In this construction, the plug 4^a has mounted in its wall, a radially disposed pin 28 to enter a hole 29 in the wall of the cylinder and to be forced into said opening by a screw driver or other instrument 30 forced into the keyway of the plug. This 55 modification is fully disclosed and claimed in my application filed on even date herewith Serial No. 159,423.

Having fully described my invention what 60 I claim as new and desire to secure by Letters Patent, is:—

1. The combination with the cylinder and plug of a cylinder lock, of means controlled by surreptitious longitudinal movement of the plug to lock said plug against turning.

2. The combination with the cylinder and plug of a lock, of a member carried by one of said parts and an element upon the other of said parts constructed to be engaged by said member, said member being movable upon attempted surreptitious operation of the plug into permanent interlocked relation to said element, whereby the plug will be prevented from normal bolt retracting operation. 70

3. In a cylinder lock, a plug and cylinder 75 having cooperative locking slots, and means cooperable with said slots and operable by attempted forceful lock operation for interlocking the plug and cylinder.

4. In a cylinder lock, normally inoperative 80 locking means on the plug and the cylinder adapted for interlocking operation, the locking means of one being movable to interlock with the other upon attempted forceful movement of the plug. 85

5. The combination with the cylinder and plug of a cylinder lock, of a locking bar carried by the cylinder and engageable by the plug to move said locking bar into locked relation to the plug and prevent turning of the 90 latter. 95

6. The combination with a lock cylinder, and a plug structure including a head and part adapted to be engaged by a locking bar, of a locking bar carried by the cylinder and engageable by the plug head to cause said locking bar to effect locked engagement with the plug and lock the latter against turning. 100

7. The combination of a lock cylinder having interior longitudinal groove, a plug, a 105 locking bar located in said groove and engageable by the plug when the latter is surreptitiously forced forwardly, and means cooperable with said locking bar to lock the plug against turning when said bar is forced forwardly. 110

8. The combination of a lock cylinder having an interior longitudinal groove, a plug having a head at one end and bar engaging means at the other end, and a locking bar located in said groove behind the head of the plug and adapted to engage the bar engaging means of the plug to lock the latter against turning when said plug is surreptitiously forced forwardly. 115

9. The combination with the cylinder and plug of a lock, of a member movable with the plug, and a member mounted in the cylinder and driven upon surreptitious operation of the plug into the path of the member on the plug whereby to prevent turning of the plug. 120

10. In a lock, the combination with a cylinder having a prepared portion and a plug having a keyway therein, of a member carried by the cylinder, and immovable relatively thereto in the normal operation of said lock, but movable by surreptitious operation of the plug through said keyway, to interlock the same with the prepared portion of the cylinder and disable the lock against operation. 125

11. In a lock, the combination with a cylinder member and die cast plug member having a keyway therein, of an element movably mounted on one of said members and movable by attempted forceful surreptitious operation of the plug through said keyway to effect permanent locking of the plug against future operation, said element remaining stationary relatively to the member which carries the same, in the normal operation of the lock.

12. In a cylinder lock, a cylinder member, a plug member having a keyway therein, and co-operative interlocking elements on the plug member and the cylinder member, one of said 15 interlocking elements being movably mounted on one of said members, but normally inoperative and adapted to be rendered operative upon attempted forceful operation of said

plug member through said keyway to permanently lock the plug against operation.

13. In a lock, the combination with a cylinder member and a plug member having a keyway therein, one of said members having a prepared portion, of a movable element carried by the other member and immovable element carried by the other member and immovable relatively thereto in the normal operation of said lock, said element being arranged to move by forceful surreptitious operation of the plug member through said keyway to 30 interlock the element with said prepared portion and disable the lock against operation.

In testimony whereof, I have signed this specification.

FREDERIC K. HEYER.
